UNITED STATES PATENT OFFICE.

GILBERT L. CROWELL, JR., OF ARLINGTON, NEW JERSEY, ASSIGNOR TO DOMINICK & HAFF, OF NEW YORK, N. Y., A JOINT STOCK ASSOCIATION.

DESIGN FOR A CANDLESTICK.

SPECIFICATION forming part of Design No. 36,187, dated January 6, 1903.

Application filed November 24, 1902. Serial No. 132,707. Term of patent 7 years.

To all whom it may concern:

Be it known that I, GILBERT L. CROWELL, Jr., a citizen of the United States, residing at Arlington, in the county of Hudson and 5 State of New Jersey, have invented a new, original, and ornamental Design for Candlesticks, of which the following is a specification, reference being had to the drawings accompanying and forming part of the same, 10 and which illustrate the design.

Figure 1 is the elevation view of the front of the candlestick, the rear of the candlestick being the same as the front. Fig. 2 is a plan view of the top of the bobache, the receptacle 15 in which the candle fits and which in turn is fitted to the top or cup of the candlestick. Fig. 3 is a plan view of the circular base of the candlestick, from which the column rises.

The general outline of the candlestick consists of a circular base A, with a column B, whose cross-section is circular and enlarged 20 in the lower and upper parts of the column, where the blossoms H are placed, as hereinafter shown, the column at its upper end 25 joining a cup C, whose cross-section is circular and to which is fitted an overhanging

bobache D, with an almost circular edge J. The base A is circular, with a slightly-waved wire F near the edge. The curving lines of the base F grow into the column B. The ornamentation is that of the conventional plant or flower, with leaves I and blossoms H and stems G, beginning on the base of the column and winding spirally around and up the column B and terminating near the top of the 35 cup C. The blossoms H appear on the enlarged portions of the column and on both the front and rear of the column. On the circular base A there are four clusters of leaves I, from which the stems G lead up and around 40 the column. On the upper surface of the bobache D the plant or flower runs around, showing two blossoms H and leaves I and connecting-stems G.

What is claimed as new is—
The ornamental design for a candlestick 45 substantially as shown and described.

GILBERT L. CROWELL, JR.
